UNITED STATES PATENT OFFICE.

CATHARINE SCHIESS, OF NEW YORK, N. Y.

DESIGN FOR AN INITIAL LETTER FOR HANDKERCHIEFS.

SPECIFICATION forming part of Design No. 19,082, dated May 7, 1889.

Application filed February 7, 1889. Serial No. 299,210. Term of patent 7 years.

To all whom it may concern:

Be it known that I, CATHARINE SCHIESS, a citizen of the United States of America, residing in the city, county, and State of New York, have invented and produced a new and original Design for Embroidered Initial Letters for Handkerchiefs, of which the following is a specification, reference being had to the accompanying drawing, which forms part thereof.

The figure is a view of a handkerchief-corner broken away, showing thereon an initial ornamental letter having leaf-shaped terminals with continuous central open-work and overlying sprays.

The leading feature of my design consists of the open-work in the center part of said embroidered initial and ornamental letter, having leaf-shaped terminals with continuous central open-work and overlying sprays, 20 the same being embroidered with silk, cotton, or linen, connecting the open-work, which, as shown, appears in squares.

What I claim is—

The design for handkerchief embroidery 25 herein shown, consisting of an initial ornamental letter having leaf-shaped terminals with continuous central open-work and overlying sprays, as set forth.

CATHARINE SCHIESS.
